UNITED STATES PATENT OFFICE.

WILLIAM M. ROUNTREE, OF NEW YORK, N. Y.

DESIGN FOR A BINNACLE.

43,084.

Specification for Design.

Patented Oct. 1, 1912.

Application filed February 19, 1912. Serial No. 678,750. Term of patent 3½ years.

To all whom it may concern:

Be it known that I, WILLIAM M. ROUNTREE, a citizen of the United States, residing in the city of New York, borough of Brooklyn, in the county of Kings and State of New York, have invented a new, original, and ornamental Design for Binnacles, shown in the accompanying drawing.

The figure is a perspective view showing my new design.

I claim:

The ornamental design for a binnacle, as shown.

WILLIAM M. ROUNTREE.

Witnesses:

HELEN V. RICE,
CHARLES R. SEARLE.
